UNITED STATES PATENT OFFICE.

DAVID P. BROWN, OF READING, MASSACHUSETTS.

DESIGN FOR A SHOE.

Specification forming part of Design No. **6,264**, dated November 19, 1872.

To all whom it may concern:

Be it known that I, DAVID P. BROWN, of Reading, in the county of Middlesex and State of Massachusetts, have invented a new and Improved Design for a Shoe; and I do hereby declare that the following specification, taken in connection with the drawing, is a full, clear, and exact description thereof.

The design relates particularly to a new form for infants' shoes, the design being, however, more or less applicable to larger shoes, and especially to ladies' and children's shoes.

In my improved shoe or form of shoe, I cut the vamp short at the front and with no tongue, and the heel and quarter piece I make high, especially at the back, and with two projecting strap-pieces, that extend over the instep, and button or buckle, leaving an open space between them for the stocking of the wearer to show prominently between the quarter-straps and the edge of the vamp, the quarter-piece being cut with a concave sweep that embraces one edge of the strap-pieces. It is in this general form or design for a shoe that my invention consists.

The drawing represents a shoe embodying the design.

a denotes the sole; *b*, the heel and quarter-piece; *c*, the vamp; *d*, one of the straps. The upper may be made of one piece, but is preferably formed with the two independent pieces *b c*. In either case the top line *e f* is well down upon or below the instep, and inclines from *e* to *f* toward the toe, while from the quarter extend two strap-pieces, *d*, by which the shoe is fastened upon the foot. The strap-pieces form part of the quarter-piece, and the quarter-piece is cut with the curve *g h i*.

The shoe thus made is very neat in appearance, fits well to the foot, and is strong and comparatively free from tendency to wrinkle.

I claim—

The design for a shoe, substantially as shown and described.

Executed this 23d day of October, A. D. 1872.

DAVID P. BROWN.
